Application May 4, 1935, Serial No. 19,817
In Germany May 9, 1934

5 Claims. (Cl. 250—27.5)

The present invention relates to a Braun tube for television purposes which is preferably operated in a highly evacuated condition, in which electro-static fields are employed throughout for producing and deflecting the image point, and in which all of the electrodes by means of which the fields are produced are arranged within the tube, so that the tube is at once in an operable condition without further external auxiliary devices, such as coils and the like.

The tube according to the invention, an embodiment of which is illustrated by way of example in Fig. 1, may, broadly speaking from the point of view of physics, be divided into three parts: first, the beam condensing device ("condenser" in an optical sense) with control grid and perforated diaphragm, secondly the reproducing lens with tubular member up to the anode, and thirdly two deflecting condensers. The indirectly heated cathode consists of a small nickel hood 1, which at its front end, the diameter of which is 2 mm., is ground completely flat and is furnished with a small recess 2 of .1 mm. only in depth, which is filled up with a highly emissive substance, for example a mixture of earth alkaline oxides, such as are well known in the art. In selecting the size of the recess 2 the size of the picture and the number of scanning lines are to be taken into consideration; the exact calculation of the size of the emissive layer will be set forth below. The glow hood 2 is heated by means of a preferably slotted spiral 3 arranged in the interior of the hood, which may be insulated from 2 by a small insulating tube (not shown) consisting for example of magnesia. The complete cathode is located exactly in axial position within a control cylinder 4 by the use of a cylindrical fitting, so that the emissive surface is exactly aligned with the tube axis. The cylinder 4, in turn, is fitted by means of two stamped collars 5 and 6 onto certain elements—for example glass rods—provided for centering the whole of the tube system in itself, and carries at a small distance from its upper end a diaphragm 7 having a narrow aperture, which diaphragm is disposed in close neighbourhood of the glow head 1, for example at a distance of within .5 mm. therefrom. The cylinder extends beyond the grid diaphragm 7 by a definite amount 8 (see below).

The cathode ray proceeding from 2 and controlled in its intensity by 1 is preliminarily concentrated by 8 and impinges on a narrow diaphragm aperture 9 of approximately the same size as the emissive surface 2. The diaphragm plate carrying the aperture 9 consists of a completely outgassed metal having a high fusing point, for example molybdenum, which preferably is welded on to a bronze supporting plate 10 to form the diaphragm proper. The support-

ing plate 10 possesses a considerably wider aperture, so that the same is not touched by the directly impinging cathode ray and a local heating of the bronze plate is prevented. In this way the danger of subsequent discharge of gas within 5 the tube is eliminated.

The aperture in the perforated diaphragm 9 onto which the cathode ray is projected with varying intensity is reproduced by an electron optical system on the screen, viz., by the electrode 10 system comprising electrodes 11, 12, 13 and 14. The main purpose of tubular member 11 (bronze) consists in screening the cathode ray traversing the interior thereof against external electrostatic fields. The length which this member is to be 15 given may be readily calculated from the desired scale of enlargement of the reproduction with a given constructional length of the tube (see below). The tubular member 11 is linked up with a lower positive bias than the main anode 14 and 20 preferably than the diaphragm 10 also. The path of the cathode ray does not undergo any electron-optical refraction within the tubular member, since in accordance with the invention the diameter of the tubular member is selected to be large 25 as compared with the diaphragm aperture 9. It is true that the applicant has been able to ascertain definitely that a wide tubular member of this kind which is biased negatively in relation to the rays is ineffective in practice only as regards rays 30 in the vicinity of the axis, i. e., the main bundle of rays, whilst as regards such marginal ray as stray to an appreciable extent it effects an auxiliary concentration which is very helpful for a satisfactory operation of the tube. It is possible, for example, to completely suppress by a 35 bias of this kind of the tubular member in relation to the diaphragm the known halation effects, which otherwise will appear on the luminous screen.

By means of an intermediate diaphragm with large aperture 12 and a short tubular extension 13 in conjunction with the double anode 14 situated in front of the tubular member the cathode ray refraction proper is produced. The peculiar form of the electrodes is the result of systematic investigations of electron-optical lenses. The problem which has been solved in this respect consisted in the first place in producing by electrical design and adjustment the effect of a 40 spherically corrected lens having for the marginal rays the same focal distance as for the central rays. Secondly no refraction should be exerted on the electrons after leaving the main anode 14, and thirdly it should be possible to 45 provide deflecting plates behind the anode without the symmetry of rotation of the lens being lost. ("Behind" means: more remote from the cathode than.)

The lens 12, 13, 14 as shown satisfies these re- 60

uirements as soon as the correct difference in potential has been adjusted between 13 and 14, 14 being maintained positive in relation to 13. This adjustment, which determines the degree of electron optical refraction, is performed by means of a potentiometer 18 which is connected with the terminal 15, and is connected between the earth potential, which is simultaneously linked up with the diaphragm 10 and the anode 14, and the potential of the cathode. The refractive field is limited to the lens space (i. e., the space between the electrodes producing the lens) by virtue of the screened construction of the lens electrodes both towards the front as well as towards the rear. The 15 apertures may preferably be made not larger than the largest cross-section of the electron bundle. The spherical correction of the lens is obtained only upon introduction of the rear intermediate diaphragm 12 into the tubular member. If the 20 width of this diaphragm 12 is made approximately as large as the tubular extension 13, the potential levels have substantially the form of an inscribed spherical surface, and the lens acts as a spherically corrected one, which is not true if the intermediate diaphragm 12 is omitted. It may be 25 added that the diaphragm 12 acts at the same time as a selection pupil by which those marginal rays are stopped which diverge too strongly.

The third requirement, viz., the independency 30 of the symmetry of the lens field from the fields of the deflecting plates arranged behind the anode 14, is obtained by increasing the axial length of the anode to a certain extent by a small tube 15. In this manner the penetration of the fields of the 35 plates arranged behind the anode 14 into the lens field is greatly reduced, and it is in fact accomplished that the stationary image point, which is produced by the use of a circular diaphragm 9, is an undisturbed round point.

40 The deflection of the cathode rays takes place by means of two plates 16, 17 in the horizontal direction, and 18, 19 in the vertical direction. The deflection is unavoidably associated with simultaneous disturbances in the sharpness of the 45 image point at the edge of the image if, as heretofore usual, the one plate being connected with the deflecting voltage generator, the other plate is earthed.

In accordance with the invention, it is possible 50 to overcome this difficulty, which heretofore has prevented the construction of tubes operating with purely electrostatic means, by operating the two plates in reverse phase with respect to each other. For this purpose there is provided a special 55 relaxation oscillation apparatus, which consists, for example as shown, of the twin amplifier tube circuit including a twin tube 20. Two independent grid-anode systems 22, 23 and 24, 25 are arranged about a common cathode. Simple single-grid systems with a reciprocal of approximately 2% in combination with a mica disc screening means 26, are fully sufficient. The one of the two systems, for example, the lower one, is connected directly with the relaxation condenser 28, which 65 is charged through the medium of the resistance 27, and discharged through the medium of a gas-filled grid-controlled discharge device 29 of that general type, a well known representative of which is the tube called "Thyratron" (registered trademark). The anode 25 of the system here in question is connected with a working resistance 30 of approximately 100,000 ohms, and with the one deflecting plate 17 of the television tube through the medium of a coupling condenser 31. In order now 70 to obtain for the other deflecting plate 16 an equal

potential of opposite phase the plate leakage resistance 32 (not exceeding 100,000 ohms) is connected with the second control, grid 22 of the upper system of the twin amplifier tube 20, the relaxation potential being reduced by means of a tapping 32', exactly to the extent to which the same has been amplified in the lower half of the tube 24, 25 (amplification factor 1/D). There is accordingly obtained at the working resistance 33 of the second anode 22 the desired reverse relaxation potential having the same amplitude but reverse phase. This reverse potential is conducted to the second deflecting plate 16 of the television tube through the medium of a second coupling condenser, this deflecting plate being also earthed 15 through a leakage resistance 34 larger than 32.

By means of a similar relaxation arrangement likewise comprising a countercadence amplifier the front pair of deflecting plates 18, 19 is also operated in reverse phase. It must be particularly emphasized that without such reverse phase circuit the problem does not appear capable of solution. The errors which then occur, i. e., in the case of the usual single phase operation are lack of sharpness at the edge by variation of the 25 focal distance, and a trapezoidal shape of the picture. These errors in the image are all avoided by reverse phase operation of the two deflecting plates. It is true that the mutual approach of the pairs of plates towards each other and the 30 anode should not be driven farther than to within two to three times the width of mouth (distance between the rear edges, directed towards the cathode, of the plates of a pair of deflecting plates).

Improvements in the operation at the plates 35 may be obtained by giving them a suitable shape. It is convenient to dispose them in a tilted position in relation to each other, as a certain gain in their specific sensitivity (deflection in mm. per volt) is thereby obtained. Beyond this the sensitivity of the deflection is, with the use of a reverse phase circuit, twice as great as with a usual circuit, i. e., the anode battery potential 35, may be half as great as usually, which is of particular 40 advantage in the case of short-ray high-vacuum tubes in which the deflecting plates require to be approached as near as possible towards the screen. It has been found that to avoid interfering 45 placement of the ray owing to wall charges a silver coating 36 should be provided, which may preferably be connected with earth, i. e., with the anode 14 or diaphragm 10. The applicant has ascertained, however, that this silver coating requires to cover merely a part of the bulb, viz., it 50 requires to extend only from the anode 14 up to the front plates 18, 19, which already project into the interior of the bulb. Equally as important as this screening is an outer magnetic screening of the tube by means of an iron shield 37, which 55 needs only to consist of a sheet of approximately 1 mm. thickness having a good magnetical conductivity, which, however, must be closed in annular form (welded or drawn), and need merely extend from the hot cathode to the anode.

The shield is preferably likewise connected with earth. It is only with the provision of this shield that it is possible to operate the tube in any desired position in relation to the magnetic earth field, so that particular potentiometers for adjusting the position of the centre of the image are unnecessary.

This lack of sensitiveness against field disturbances is favoured by the extensive preliminary acceleration of the ray which is effected accord-

ing to the invention by the high positive potential of the diaphragm 9.

The light intensity and function of the whole tube is essentially determined by the path of the rays between cathode and diaphragm. The rays should be suitably influenced in this particular region, i. e., in such manner that as far as possible all electrons in the first place are passed through the narrow aperture, and secondly continue to move in such a narrow cone that no stopping of electrons occurs later neither in the lens nor in the diaphragm and that all electrons reach the screen in one definite image point. The better the form of the bundle obtained, the more sensitive the deflection may be made, as a bundle having a small cross section in the plate field practically is not subject to disturbances even in highly sensitive plate systems, whilst a bundle having a large cross section in the region in question undergoes lateral distortions in such systems.

The applicant has found that the simple condensing lens 7, 8, 10 as shown, which exactly corresponds in its operation with the main lens 12, 13, 14, is capable of fulfilling the stated requirements, but merely under the condition that the free length of the ray between cathode and diaphragm is not too small. The applicant has found that the spacing 7/10 must amount to at least 10 mm. This spacing is calculated in practice by use of the simple diopter law on the basis of the required width of bundle. One may in fact obtain a survey on the conditions of ray propagation as influenced by the condensing lens by drawing the most unfavourable rays from the edge of the cathode spot over the edge of the diaphragm aperture. These rays must then undergo such a refraction in the condensing lenses as to pass through the image producing lens and through the space between the deflecting plates.

With a large spacing 7/10 as stated above and the cylinder extension 8 necessary for spherically correcting the condensing lens, which extension fills out approximately one-half of the spacing, it is clear that the anode field attracting the electrons is rather weakened. If only for this reason alone the separate and sufficiently strong positive bias of the diaphragm 10 is essential if it is desired to obtain bright images. In particular cases it may be necessary to provide a screening grid diaphragm 38 together with a particular intermediate cylinder 39, in order to be able to make the requirement for suitably guiding of the ray unobstructedly consistent with the requirement for sufficient anodic strength of field as is necessary for producing cathode rays of great intensity.

In the following it will be set forth in what manner a tube according to the invention may be dimensioned in practice.

60 Cathode spot mm .4
Maximum total emission mA .8
Diameter of aperture in grid diaphragm
7 mm .2
65 Diameter of the front surface of cathode mm .1.8
Spacing between grid and front surface of cathode mm .5
Cylinder extension 8 mm .3
70 Spacing between edge of cylinder and dia- phragm 10 mm .7
Diameter of aperture in diaphragm 10 for 180-line picture size 14x18 mm .4
Diameter of aperture in diaphragm for 180- 75 line picture size 17x20 mm .5

Form of aperture is reproduced sharply; therefore also square or hexagonal apertures may be used.

Current utilization	^{75% with diaphragm .4} ^{90% with diaphragm .5}	5
Length of tubular member 11 approxi- mately	mm 100	
Diameter of aperture of lens 11, 12	mm 7	
Tubular member extension 13	mm 7	
Diameter of tubular member	mm 20	10
Spacing between edge of tubular member and anode	mm 7	
Diameter of anode tube 15	mm 7	
Length of anode tube 15	mm 7	
Space between anode 15 and edge of rear deflecting plate	mm 15	
Width of mouth of rear deflecting plates system	mm 6 and 15	
Length of rear deflecting plates	mm 35	20
Width of mouth of front deflecting plates system	mm 6 and 20	
Distance between rear plates system and front plates system	mm 20	
Spacing between anode 15 and luminous screen	mm 250	25
Anode potential	volts 2,000	
Maximum power required	watt 1	
Heating 4 volts, A. C. or D. C.	amp .4	
Potential of tubular member, volts variable, approx.	1,500	30
Sensitivity of deflection per volt, approx.	mm .5	
Voltage of supply battery of relaxation oscil- lation generator 35	volts 800	

It is to be understood that the above data only refer to a particular form of embodiment of the tube according to the invention, to which the invention is in no way limited.

The individual parts of the system may be mounted on the base of the tube and centered in relation to each other preferably by the use of insulating supporting means, which may preferably consist of glass. The individual current leads are preferably all taken to a socket secured to the base of the tube. The current supply to the metallic coating 36 is preferably effected so as to avoid special fusing-in points by means of springs fixed to the electrode system and conductively connected for example with the anode. These springs may at the same time serve for supporting or guiding the system within the neck of the tube. For this purpose they may be constructed for example in the form of comparatively strong, bent blade springs.

A practical and convenient technical form of embodiment of the tube according to the invention is illustrated by way of example in Fig. 2, like references being given to like parts in the two figures.

I claim:

1. A Braun tube more particularly for television purposes comprising means including a cathode disposed near one end of the tube for producing a cathode ray, an image screen disposed at the end of the tube opposite to that end near which said cathode is disposed, and an electron-optical lens system for projecting the cathode ray onto said image screen in the form of a sharply defined image point, said electron-optical lens system comprising a tubular member having its axis disposed in the direction from said cathode to said screen and having a diameter which is considerably larger than the diameter which the cathode ray possesses when travelling through said tubular member, an apertured disc shaped

60

65

70

75

anode mounted perpendicularly to the axis of said tubular member, near said tubular member between said tubular member and said image screen, and an apertured diaphragm separating said tubular member into two parts and being mounted near that edge of said tubular member facing said anode, said anode being adapted to be supplied with a high positive potential in relation to said cathode, said tubular member being adapted to be supplied with a potential positive in relation to said cathode but negative in relation to said anode.

2. A Braun tube more particularly for television purposes comprising means including a cathode disposed near one end of the tube for producing a cathode ray, an image screen disposed at the end of the tube opposite to that end near which said cathode is disposed, and an electron-optical lens system for projecting the cathode ray onto said image screen in the form of a sharply defined image point, said electron-optical lens system comprising a tubular member having its axis disposed in the direction from said cathode to said screen and having a diameter which is considerably larger than the diameter which the cathode ray possesses when travelling through said tubular member, an anode mounted near said tubular member between said tubular member and said image screen, said anode comprising at its side facing said tubular member an apertured plate shaped portion disposed perpendicularly to the axis of said tubular member, said anode having a tube-like extension in the direction away from said tubular member, and an apertured diaphragm separating said tubular member into two parts and being mounted near that edge of said tubular member facing said anode, said anode being adapted to be supplied with a high positive potential in relation to said cathode, said tubular member being adapted to be supplied with a potential positive in relation to said cathode but negative in relation to said anode.

3. A Braun tube more particularly for television purposes comprising means for producing a cathode ray, means to produce different electric fields for influencing the cathode ray in different axially consecutive zones of the tube, an image screen disposed at one end of the tube to be hit by the cathode ray after the cathode ray has passed through the mentioned axially consecutive zones, an electrode system located in a space of the Braun tube, both at the sides of which space facing said screen and facing away from said screen at least one of said fields is located, said electrode system comprising electrodes adapted to produce an electron-optically refractive field, and to at the same time screen this refractive field against the fields at the side of said electrode system facing said screen as well as at the side of said electrode system facing away from said screen, said electrode system comprising a tubular member having its axis directed towards said screen and having a diameter which is considerably larger than the diameter which the cathode ray possesses when travelling through said tubular member, an apertured disc shaped anode mounted perpendicularly to the axis of said tubular member near said tubular member between said tubular member and said image screen, and an apertured diaphragm separating said tubular member into two parts and being mounted near that edge of said tubular

member facing said anode, said anode being adapted to be supplied with a high positive potential in relation to said cathode, said tubular member being adapted to be supplied with a potential positive in relation to said cathode but negative in relation to said anode.

4. A Braun tube more particularly for television purposes comprising means including a cathode disposed near one end of the tube for producing a cathode ray, an image screen disposed at the end of the tube opposite to that end near which said cathode is disposed, and an electron-optical lens system for projecting the cathode ray onto said image screen in the form of a sharply defined image point, said electron-optical lens system comprising a tubular member having its axis disposed in the direction from said cathode to said screen and having a diameter which is considerably larger than the diameter which the cathode ray possesses when travelling through said tubular member, an apertured disc-shaped anode mounted perpendicularly to the axis of said tubular member near said tubular member between said tubular member and said image screen, and an apertured diaphragm separating said tubular member into two parts and being mounted near that edge of said tubular member facing said anode, both said anode and said apertured diaphragm having apertures the cross-sections of which are substantially equal to the cross-sections which the cathode ray has in the respective planes of said apertures, said anode being adapted to be supplied with a high positive potential in relation to said cathode, said tubular member being adapted to be supplied with a potential positive in relation to said cathode but negative in relation to said anode.

5. A Braun tube more particularly for television purposes comprising means including a cathode disposed near one end of the tube for producing a cathode ray, an image screen disposed at the end of the tube opposite to that end near which said cathode is disposed, and an electron-optical lens system for projecting the cathode ray onto said image screen in the form of a sharply defined image point, said electron-optical lens system comprising a tubular member having its axis disposed in the direction from said cathode to said screen and having a diameter which is considerably larger than the diameter which the cathode ray possesses when traveling through said tubular member, an apertured disc shaped anode mounted perpendicularly to the axis of said tubular member near said tubular member between said tubular member and said image screen, and an apertured diaphragm separating said tubular member into two parts and being mounted near that edge of said tubular member facing said anode, both said anode and said apertured diaphragm having apertures the cross-sections of which are substantially equal to the cross-sections which the cathode ray has in the respective planes of said apertures, the distance of said apertured diaphragm from the edge of said tubular member facing said anode being approximately equal to the diameter of the aperture in said apertured diaphragm, said anode being adapted to be supplied with a high positive potential in relation to said cathode, said tubular member being adapted to be supplied with a potential positive in relation to said cathode but negative in relation to said anode.

KURT SCHLESINGER.
